UNITED STATES PATENT OFFICE.

JOHANN G. PETERSON, OF HARTFORD, CONNECTICUT.

ELECTRIC SWITCH.

1,032,767.

Specification of Letters Patent. Patented July 16, 1912.

Application filed October 19, 1911. Serial No. 655,449.

To all whom it may concern:

Be it known that I, JOHANN G. PETERSON, a citizen of the United States, residing at Hartford, in the county of Hartford and State of Connecticut, have invented certain new and useful Improvements in Electric Switches, of which the following is a specification.

This invention relates to electric switches, the object of the invention being to provide an article of this character which is simple in construction and effective and certain in action.

The device possesses other features of advantage and novelty which with the foregoing will be set forth in full wherein I will outline that form of embodiment of the invention which I have selected for illustration in the drawings accompanying and forming part of the present specification, this disclosure being primarily provided to enable those skilled in the art to practice the invention. From the observation just made it will be clear that I do not restrict myself to said showing; I may depart therefrom in several respects within the scope of the invention included in the claims following said description.

Referring to said drawings: Figure 1 is a sectional view of a switch including my invention. Fig. 2 is a cross sectional view on the line 2—2 of Fig. 1. Fig. 3 is a sectional diagrammatic view of the carrier, rocker, locking plate and certain adjunctive parts showing by dotted lines certain actions which occur in the operation of the switch as will hereinafter appear. Figs. 4 and 5 are detail views partly in section and partly in elevation of the carrier, rocker and locking plate in different positions. Fig. 6 is a sectional view of the rocker, and, Fig. 7 is a face view of the same.

Like characters refer to like parts throughout the several views.

The different parts of a switch involving my invention, except as to the push buttons, are inclosed in a boxing or casing such as that denoted in a general way by 10 to the top of which there may be connected as shown a bracket 11 which directly sustains the several moving parts of the switch and which as is customary may be in the form of a yoke, the side branches of which carry a spindle 12.

Loosely supported by the spindle 12 is an approximately yoke or U-shaped member 13,

the arms of said member 13 being sleeved upon said spindle in the construction shown, at points outside the bracket 11 and being engaged by washers 14 held by pins each denoted by 14', which pins prevent accidental longitudinal movement of said spindle and therefore displacement thereof. One of the upright branches of said element 13 is provided with blades or arms 15 and 16 coöperative with contacts 17 and 18 fastened within the body of the case 10 which is usually made of some insulating material such as any of the compositions now familiar in the art. Lead wires (not shown) are connected with these contacts 17 and 18, and it will be understood that when the blades 15 and 16 bridge the two contacts the circuit controlled by the switch will be closed, said circuit being illustrated as open in Fig. 1. The part to which blades such as 15 and 16 are connected is usually known as a "carrier," and the member 13 will, therefore, be hereinafter termed such or as the switch proper or circuit closing instrumentalities of the switch.

It might be desirable at this point to indicate that although the invention is shown incorporated in a push switch it may be employed with equal utility in other kinds of switches. It is customary in a push switch to provide what is known as a rocker and the rocker 19 satisfactorily meets the conditions, the body of said rocker, which is practically in the form of a disk having oppositely disposed arms 20 and 21 to which the levers 22 and 23 are pivoted, said levers being equipped with buttons each denoted by 24 by which said levers and hence the rocker can be operated. The rocker 19 has a central opening to rigidly receive the reduced end of the sleeve 25 mounted freely upon the spindle 12, it being understood that the rocker 19 is situated between the branches of the bracket 11. The rocker 19 in addition to the oppositely disposed arms 20 and 21 has a third arm 26 provided with a lug 27 which swings through an arc concentric with the arc through which the transverse portion of the carrier 13 moves. The body of a coiled spring 28 surrounds the sleeve 25, the ends of said body having projections 29 and 30 which normally engage the lug 27 and the transverse portion of the carrier 13 and tend to hold the same in radial alignment.

In Fig. 1 the parts are represented as oc-

cupying a normal position, the carrier 13 at this time being positively locked against movement; it will be assumed that it is desired to close the circuit. In this event the 5 button 24 of the lever 22 is manually thrust inward. As said button is thus actuated the arm 20 is swung down, thereby moving the lug 27 to the right in Fig. 1 and hence carrying the projection 29 therewith so as to tension the spring 28. When the lever 22 has completed its maximum inward movement as will hereinafter appear, the carrier 13 is released so that the projection 30 of the 10 spring, which at this time is under maximum tension, can act against the transverse portion of the carrier 13 and thereby shift said carrier to cause the blades 15 and 16 to engage the coöperating contacts 17 and 18 and hence close the circuit. To open the 15 circuit the action described will be reversed.

A locking member such as the plate 31 governs the carrier 13. Said locking plate has oppositely disposed arms each denoted by 32 provided with outwardly bent lugs 33 20 and 34 which travel in slots formed in the outer branch of the leg of the yoke-like bracket 11 and thereby guide said locking plate and also prevent the same from moving laterally. The body of the locking plate 31 is contiguous to the inner surface of the outer branch of said bracket 11, and its inner surface is engaged or approximately engaged by the rocker 19 so that the cam slot 35 in said locking plate or body is covered 25 or inclosed. This slot will be hereinafter more particularly described, although it is desirable to state at this time that owing to the fact that it is thus closed in, it presents an effective chamber for retaining lubricant 30 employed for lubricating the devices also hereinafter described which move in said slot. The carrier 13 has an outward extension 36 constituting a catch portion and engageable by the stop lug 34 to which reference has already been made. In Fig. 1 the 35 lug 34 is shown engaging the extension or catch portion 36 so as to thereby hold the carrier 13 in circuit opening position. As the lever 22 is thrust inward in the manner 40 already described, the lug 34 as will hereinafter appear will be given a reciprocation being first moved inward a comparatively short distance and then outward and when the maximum outward movement of said lug 45 34 has taken place under the primary action of the operator, the carrier 13 will be released, the spring 28 having in the meantime been tensioned, so that said carrier can be swung over as already described by the 50 power of said spring. As intimated it requires a full inward movement of either the lever 22 (or the lever 23) by the appropriate push button to effect the release of the carrier and the parts are so proportioned that 55 60 65 when such releasing action is secured pri-

marily through manual influence, the rocker will be moved beyond the point to which the carrier is subsequently shifted, and on this particular motion of said rocker the spring will be further tensioned so that when the 70 push button thus operated is released, the spring becomes effective for shifting the rocker and thereby the locking plate to such position that the stop or locking lug 34 will be in its holding or effective relation. The 75 locking plate 31 is therefore moved to releasing position by hand aided by cam mechanism as will now appear, and is restored or moved to locking position by the power of the spring so that owing to this fact I need 80 employ but a single spring to operate the blade carrier and locking plate. The rocker 19 is provided with projections 37, 38 and 39 which are of substantially circular form and which may as a matter of simplicity and in- 85 expensiveness, be punched from the body of the rocker, said projections or lugs being located within the cam slot 35 and acting against cam faces upon the wall of said slot. I might remark that these are the cam 90 surfaces and projections that I desire to lubricate. The cam slot 35 has at one end thereof the inclined surfaces 40 and 41 which merge to produce a wedge-like cam. At the opposite end of said slot are inclined 95 surfaces 42 and 43 connected by a flat face 44 the surfaces 42, 43 and 44 presenting in effect a truncated wedge cam, the two wedge cams being united by the concave surfaces 45 and 46, the ends of which merge into the 100 respective wedge cams.

In Fig. 1 the parts are in one of their normal positions the button of the lever 22 being out, while that of the lever 23 is in. As the lever 22 is moved inward to close the circuit, the rocker 19 is oscillated thereby causing the projection 38 to ride along the inclined surface 40 and thus move the locking plate 31 inward, the movement being completed when the projection 38 reaches the apex of the wedge presented by the surface 44 and 41 as indicated in Fig. 4. Shortly after this time the projection 39 will ride against the cam surface 42 as shown in Fig. 5 and as said projection 39 continues to ride 110 along such surface 42 the locking plate 31 will be moved outward thereby carrying the locking stop or lug 34 free of the catch portion 36 as indicated in Fig. 5. In the action described the locking lug 34 is given a full 115 stroke or a complete reciprocation and during this particular motion the lug 27 will be swung on the inward movement of the lever 22 alternately beyond the points which it normally occupies. The instant that the lug 34 disengages the catch portion 36, the carrier 13 will be shifted in the manner already described and just following this the projection 29 of the spring becomes effective for swing- 120 ing said lug 27 back into line with the trans- 130

verse portion of the carrier 13 so that the rocker 19 is thereby operated and said rocker acting on the locking plate 31 will move said locking plate to carry the locking lug inward and therefore into the arc or path of movement of the catch portion 36. In the slight interval between the points at which the projection 38 and the projections 37 and 39 are operating the locking plate the spring is being tensioned whereby it can subsequently move said locking plate to locking position. On the opposite motion the reverse action takes place, it being evident that at all times the locking plate is effectually held against accidental movement.

In Fig. 3 I have shown diagrammatically the action. I have represented in said figure by dotted lines in the upper part thereof the maximum movements of the buttons of the two levers. Each button as will be clear has two stages of movements, the sum of which is sufficient to cause the release of the carrier 12. In this Fig. 3 said two stages are denoted by the characters A and B. To release the carrier each button has to move a distance at least corresponding to the distance between the lines C and D to effect the tripping action and in this tripping action the rocker 19 and hence the projection portion 30 of the spring are shifted to the dotted line positions in said Fig. 3, the locking plate in the meantime having been released. When the pressure of the finger is taken from the button on the right in said Fig. 3 the spring 28 through the projection 30 will act on the lug 27 to swing the rocker 19 to normal position and as said rocker thus moves the projection 38 by acting against the cam surface 40 at the base thereof can move the locking plate 31 downward and hence cause the lug 34 to assume its locking position.

What I claim is:

1. In a switch, the combination of a blade carrier, a locking member for said blade carrier, having a slot, the wall of the slot having two wedge cam portions, and a rocker having three projections one of the projections being adapted to alternately engage the sides of one of said wedge cam portions, 45 and the two other projections being adapted to alternately engage opposite sides of the other wedge cam portion as the rocker is given a full oscillation whereby the locking member will be given two distinct reciprocations. 50 55

2. In a switch, the combination of a blade carrier, a locking member for said blade carrier having two separate cam portions, a rocker provided with means for engaging 60 said cam portions to thereby move the locking member first in one direction and then in the opposite direction to thereby effect the release of said blade carrier, a spring for applying its effect to said locking member, 65 and means for putting said spring under tension in the interval between the points at which said cam portions are operated.

3. In a switch, the combination of a support, a blade carrier on said support, a locking member for the blade carrier having a cam slot, the locking member upon one side being contiguous to said support, and a rocker fitting against the other side of said locking member, the rocker having projecting means entering said slot for engaging 70 the cam portion of said slot to thereby move the locking member to releasing position. 75

In testimony whereof I affix my signature in presence of two witnesses.

JOHANN G. PETERSON.
